US0D1085158S

(12) United States Design Patent (10) Patent No.: US D1,085,158 S
(45) Date of Patent: * Jul. 22, 2025

(54) DISPLAY SCREEN OR PORTION THEREOF WITH ICON

(71) Applicant: Welch Allyn, Inc., Skaneateles Falls, NY (US)

(72) Inventor: Stephen M. Rosa, East Providence, RI (US)

(73) Assignee: WELCH ALLYN, INC., Skaneateles Falls, NY (US)

() Term: 15 Years

(21) Appl. No.: 29/946,307

(22) Filed: Jun. 7, 2024

Related U.S. Application Data

(63) Continuation of application No. 29/784,350, filed on May 19, 2021, now Pat. No. Des. 1,044,866.

CLAIM

The ornamental design for a display screen or portion thereof with icon as shown and described.

DESCRIPTION

The patent or application file contains at least one drawing executed in color. Copies of this patent or patent application publication with color drawing(s) will be provided by the Office upon request and payment of the necessary fee.

FIG. 1 is a front plan view of an embodiment of a display screen or portion thereof with icon showing the new design; and,

FIG. 2 is a front plan view of another embodiment of a display screen or portion thereof with icon of the new design.

The dash-dot-dash broken lines of FIG. 1 depict a boundary of the display screen or portion thereof and form no part of the claimed design.

The dash-dot-dash broken lines of FIG. 2 depict a boundary of the claimed design and form no part of the claimed design. The dash-dash broken lines of FIG. 2 depict the display screen or portion thereof and form no part of the claimed design.
